UNITED STATES PATENT OFFICE.

FRANK G. WAGNER, OF LOS ANGELES, CALIFORNIA.

FOLDING SQUARE.

1,245,539.

Specification of Letters Patent.

Patented Nov. 6, 1917.

Application filed August 15, 1916. Serial No. 115,017.

To all whom it may concern:

Be it known that I, FRANK G. WAGNER, a citizen of the United States, residing at Los Angeles, California, have invented a certain new and useful Improvement in Folding Squares, of which the following is a specification.

My invention relates to squares, and consists of the novel features herein shown, described and claimed.

Figure 1 is a plan view of a folding square embodying the principles of my invention, with the parts in their normal square positions.

Fig. 2 is a fragmentary view analogous to Fig. 1 with the parts folded to make an angle of 45 degrees.

Fig. 3 is an enlarged cross-sectional detail on the line 3—3 of Fig. 2.

Fig. 4 is an enlarged edge view looking in the direction indicated by the arrows 4 in Figs. 2 and 5, and showing the parts latched in square position.

Fig. 5 is a fragmentary plan section on a plane parallel with Figs. 1 and 2 and on the line 5—5 of Fig. 4 and looking in the direction of the arrows.

The primary leg 1 and the secondary leg 2, when abutted together at their heads on the line 3, make a standard framing square, and the object of my invention is to join said legs so that they may be folded to parallel positions or set at any angle between parallel and 90 degrees or right angle.

The point 4, the inner end of the line 3, is the center upon which the secondary leg 2 swings relative to the primary leg 1, said point 4 being the inner corner of the secondary leg 2 at the abutting end. A slide-

way 5 is formed from the side face of the primary leg 1 concentric to the point 4, thus leaving a half-round pivot 6, said slideway 5 describing a semi-circle in plan terminating at the side edge of the primary leg 1, and said slideway being rectangular in cross-section. A recess 7 is formed from the same side of the secondary leg 2 to match the slideway 5. The legs may be placed together edgewise as in their folded positions or as

in their square positions and then the slideway 5 and the recess 7 may be turned or milled at the same time with the same tool, thus insuring a match. The tongue 8 is exactly three-quarters of a circle in plan and rectangular in cross-section and fits tightly in the recess 7 and is rigidly secured therein

by brazing, soldering or riveting or the like, and said tongue fits slidably in the slideway 5, so as to form a hinged connection between the legs 1 and 2, the center of the hinge being the point 4. Forming the recess 7 leaves the quarter-round supporting stud 9, matching the half-round pivot 6, and the central opening 10 in the tongue 8 is small enough to fit tight around the pivot 6 and the stud 9 so that the corner of the secondary leg 2 will press tightly against the edge of the primary leg 1 at the point 4, at all times so as to prevent yielding or shaking of one leg relative to the other and so as to make a good friction joint.

The screw-threaded clamping stud 11 is fixed through the metal of the primary leg 1 and projects through the slideway 5 at its cross-sectional center and at a point at an angle of 45 degrees toward the head end of the leg 1 from the point 4. A slot 12 is formed through the extending part of the tongue 8, said slot being concentric in plan and the stud 11 being at the cross-sectional center of the slot, and said slot being stepped in cross-section to form the retaining flanges 13 and 14 extending toward the stud 11 at the bottom of the slot 12 and against the metal at the bottom of the slideway 5. A kidney shaped washer 15 is stepped all the way around to fit slidingly in the slot 12 and to fit the flanges 13 and 14 and to extend between said flanges and jam against the metal at the bottom of the slideway and said washer has a central opening fitting the stud 11 and a recess in its upper or outer face to receive the nut 16 upon the stud 11, said nut being slotted to receive a spanner key for operating the nut.

The parts are accurately made so that when the nut is tightened the washer jams against the metal around the stud and makes a good friction fit to allow the tongue to slide in the slideway without shaking. The legs may be readily separated by removing the nut. When finished the faces are all substantially flush.

The parts thus constructed and assembled make a complete folding square with a friction joint. If the nut is thinned so that it will not jam against the bottom then the parts may be clamped in any adjusted position by tightening the nut.

In order to hold the parts rigid and exact in their square positions and not depend upon the friction joint I provide a latch-

ing mechanism 17. A latch chamber 18 is formed from the outside edge of the head of the secondary leg 2 to receive the latch bar 19 and form a stop 20 and a spring seat 21. The expansive coil spring 22 is placed in the spring seat 21, the latch bar 19 is placed in the chamber against the stop 20 with its outer face flush with the outer face of the leg and said latch bar is secured 10 in place by the pivot pin 23, and said latch bar 19 has a hook 24 extending beyond the end face of the secondary leg. A hook chamber 25 is formed from the end face of the head of the primary leg 1 and a latch pin 26 is fixed in position to extend through the hook chamber and be engaged by the hook 24, said hook being beveled to snap over the pin to normal position. In end elevation as in Fig. 4 the latch fits the chamber except that there are two recesses one upon either side of the latch 27 to receive the end of the operator's finger for pressing inwardly to release the latch.

An indicator mark 28 is formed upon the 25 primary leg 1 in transverse alinement with the point 4 and the space upon the tongue 8 which passes this indicator has the graduations 29 reading from 0 to 90, being a quarter of a circle, so that the square may be 30 used as a protractor. The remaining quadrant of the extending tongue 8 has the roof pitch scale graduations 30 reading 1—6, 1—4, 1—3, 1—2, 2—3, 3—4.

I claim:

35 1. In a folding square, a primary leg having a slideway semi-circular in plan extending from the inner edge of its head and leaving a semi-circular pivot; a screw-

threaded stud extending through said slideway; a secondary leg having a recess extending from its end and matching the slideway; a tongue fixed in the recess and slidingly fixed in the slideway and having a slot for said stud; and a washer and a nut on the stud. 40 45

2. In a folding square, a primary leg having a slideway semi-circular in plan extending from the inner edge of its head and leaving a semi-circular pivot; a screw-threaded stud extending through said slideway; a secondary leg having a recess extending from its end and matching the slideway and leaving a quarter-round stud fitting the half-round pivot; a tongue fixed in the recess and slidingly fixed in the slideway and holding the corner of said quarter-round stud tightly against the flat side of the half-round pivot and having a slot for the screw-threaded stud; and a nut upon the stud and a washer upon said stud and 60 beneath said nut. 50 55

3. In a folding square, a primary leg having a slideway semi-circular in plan extending from the inner edge of its head and leaving a semi-circular pivot; a screw-threaded stud extending through said slideway; a secondary leg having a recess extending from its end and matching the slideway; a tongue fixed in the recess and slidingly fixed in the slideway and having a stepped slot for said stud; a washer in said stepped slot around said stud; and a nut upon the stud and recessed into the washer. 65 70

In testimony whereof I affix my signature.

FRANK G. WAGNER.
